(57) **CLAIM**

The ornamental design for an lower body garment central panel piece, substantially as shown and described.

DESCRIPTION

FIG. 1 is a top rear perspective view of a lower body garment central panel piece of the present invention, as it may be used in an undergarment;

FIG. 2 is a plan enlarged view of the claimed lower body garment panel piece design;

FIG. 3 is a front elevational enlarged view of the claimed lower body garment panel piece design;

FIG. 4 is a rear elevational enlarged view of the claimed lower body garment panel piece design;

FIG. 5 is a right side elevational enlarged view of the claimed lower body garment panel piece design (the left side elevational enlarged view is a mirror image thereof); and,

FIG. 6 is a top rear perspective view of the claimed lower body garment panel piece design, as it may be used in an undergarment.

The broken lines shown on the lower body garment central panel piece and on the undergarment represent unclaimed features. The hatching shown in the drawings, while shown intermittently, is understood to cover the surface upon which it is applied in its entirety, up to but not including unclaimed edges.
